DEVICE FOR INJECTING LIQUID INTO A CAVITY OF THE HUMAN BODY

Filed Aug. 25, 1928

UNITED STATES PATENT OFFICE

PETER SCHLUMBOHM, OF BERLIN, GERMANY

DEVICE FOR INJECTING LIQUID INTO A CAVITY OF THE HUMAN BODY

Application filed August 25, 1928, Serial No. 301,981, and in Germany February 21, 1928.

My invention relates to rinsing or injecting devices and more particularly to an improved device for injecting suitable liquids into cavities of the human body especially 5 the vagina.

Injecting devices for the stated purpose comprising a rubber tube are universally known, but they cannot be used except in connection with a particular frame, so that they 10 are unpractical and unsuitable for use by travelling persons.

The chief object of my invention is to obviate this drawback and with this object in view I so construct the improved device that 15 all parts thereof consist of rubber or similar material so as to be collapsible and foldable and rigid parts are entirely avoided therein.

I shall now describe my invention more in detail in connection with the embodiments 20 thereof illustrated by way of example on the accompanying drawings forming a part of this specification and wherein the same reference symbols are used in the different figures to denote corresponding parts:

25 Figure 1 is a side view of the device,
Figure 2 is a plan thereof,

Figure 3 is a side view similar to Fig. 1 of a modification,

30 Figure 4 is a plan view of another modification and

Figure 5 is a side view thereof.

Referring to the modification shown in Figs. 1 and 2 the numeral 1 indicates a 35 cushion-like container provided with a tubular inlet or orifice 2 for filling the same with pure water or any other appropriate sanitary liquid. The orifice is to be provided with a detachable stopper (not shown) ensuring a tight seat when screwed into the orifice after 40 the container has been filled with the liquid.

The front face or wall of the container is equipped with a rubber tube 3 for discharging purpose and a suitable valve-controlled tubular injecting nozzle (not shown) of the 45 usual kind may be attached to the free

end of the tube 3 for the injecting purpose.

Integral with the front-end or wall of the cushion-like container is a tub-like member or structure 4, which preferably is of less height than the container. In the embodiment shown 50 the height of the same amounts to about one-half of that of the container. The tub 4 serves for the reception of the liquid consumed during the rinsing operation. The latter is as follows:

Preparatory to use the container 1 is to be filled with pure water or any other suitable liquid, whereupon the orifice 2 thereof is hermetically sealed, and the thus prepared device placed on a chair or a bench. The 55 person, who is going to use the device, then takes her seat on the container or cushion so that the rubber tube 3 will project between her limbs while the weight of her body will exert a pressure on the container and the 60 liquid body enclosed therein. Upon insertion of the nozzle of the tube into the vagina as usually done with injection-devices for hygienic or medicinal purposes, the valve of the 65 nozzle is to be opened so that under the pressure 70 exercised on the container the liquid will flow through the tube 3 and out of the nozzle into the vagina and thence down into the tub 4. The capacity of the container 1 is calculated to hold at least twice the quantity of 75 liquid required for an injecting operation, consequently the container will be pressed down by the person sitting thereon, to half of its height only during application and the side walls of the container will maintain a 80 practically erect position even after the operation has been finished.

In order to ensure this particularity of the container to a higher degree to afford a comfortable seat and minimize the consumption 85 of liquid at all events I prefer to provide a horizontal partition 5 in the container as shown in the modification of Figure 3. It will be seen that the container is thereby subdivided into two superposed sections or com- 90

partments 6 and 7 which are to be filled with the liquid separately by means of orifices 2^a and 2^b, respectively, of the same kind as described with reference to Figures 1 and 2. 5 The flexible tube 9 which in all respects may be identical with the tube 3, is attached to the upper compartment 6 so that only the liquid contained in the compartment 6 can be caused to escape through the tube 9 and the 10 water-filled compartment 7 forming the rear wall of the tub 8 serves as a sitting cushion only.

All parts of the device herein described and shown are made of rubber inasmuch as they 15 constitute a unit that is to say, with the exception of the detachable or subordinate parts such as the spraying nozzle, the valve thereof and, if required or preferred, the tubular inlet or orifice and its stopper. Thus also the intermediate wall or partition 5 consists of a 20 rubber sheet which is firmly attached to the wall of the container by means of rubber-solution or in any other appropriate way. When the device is out of use and the liquid discharged from the container or the compartments thereof the latter collapses and can be folded up so as to partially lie within the tub 4 or 8 with the tube 3 or 9 underneath on the bottom of the latter which thus forms a kind 25 of a pocket for the accommodation of the container so that the device will occupy little room and can be readily packed up in a box or the like for travelling purposes. To this 30 end also flaps, buttons and button-holes may be provided at suitable places for holding the device in folded condition.

In the preferred modification shown in 35 Figures 4 and 5 improved devices comprise two separate hollow bodies adapted to be filled with water or the like, and detachably interconnected by means of flaps and button 40 17, the one body or parts 10 serving as a supporting seat-cushion properly speaking and the other body or part 12 corresponding 45 to the compartment 6 in Figure 3, as regards purpose and operation. It will be seen in 50 Figures 4 and 5, that the upper body 12 exactly corresponds as regards shape and size to the rear portion of the lower body so that 55 a person sitting on the container 12, shown in Figure 5, will be afforded a properly cushioned seat even when the container 12 is emptied. In accordance, therewith the container 12 is bean-shaped in order to conform to 60 the curved rear portion of the triangular vessel or hollow supporting cushion 10. This bipartite construction of the device allows of using the container 12, when detached from 65 supporting cushion 10, as a hot-water or warming bed-pan, so that the embodiment shown in Figures 4 and 5 is the most practical.

The lower side of the annular cushion 10 is 70 provided with a sheet of rubber or rubberized cloth 11 firmly attached to the cushion by 75 means of rubber solution or in any other

suitable manner so as to form the bottom of the tub required for receiving the used water or liquid. The curved rear portion of the cushion is a little enlarged as compared with the front end thereof and has a somewhat greater diameter than the latter, gradually decreasing towards the front-end. The container 12 which as above stated, may be used separately as a bed-pan, is provided with a funnel-shaped enlargement 13 of the orifice 70 equipped, as usually, with a preferably screw-threaded sealing stopper (not shown). The one end of the injecting tube 14 is provided with a threaded end-piece (not shown) 75 of conventional form adapted to be screwed into the threaded orifice, when the container or bag 12 is filled with the injection fluid in order to be used for an injection and the other end of the tube 14 is equipped with an injecting nozzle 15 and a valve 18 as usual.

The operation is the same as hereinbefore described with reference to Figures 1 to 3. The weight of the person seated on the container 12 acts to force the liquid through the tube 14 and out of the nozzle 15, when the valve is opened and the used injection liquid is received by the tub or bottom 11, a means such as an outlet tube 16 being provided therein for the discharging purpose. It will be seen that the container 12, while being gradually emptied under the weight of the person sitting thereon will correspondingly collapse, but the collapsed container will nevertheless afford a permanently comfortable seat and prevent the person from coming in contact with the used liquid in the tub.

What I claim is:

1. A device for the injection of a liquid into a cavity of the human body comprising a container for the liquid adapted to be hermetically sealed and used as a seat-cushion, a horizontal partition in the said container arranged to form two superposed compartments, an injection-tube firmly attached to the upper compartment, and a tub connected with the lower compartment, all parts being made of rubber.

2. A device for the injection of a liquid into a cavity of the human body, comprising a container for the liquid adapted to be hermetically sealed and used as a seat-cushion, an injection-tube connected with the said container, a tub including an annular vessel adapted to be hermetically sealed and a bottom sheet attached thereto, the said vessel constituting a supporting cushion for the said container shaped to conform to the shape of the rear portion of the said vessel, all parts being made of rubber.

3. A device for the injection of a liquid into a cavity of the human body, comprising a container for the liquid adapted to be hermetically sealed and used as a seat-cushion, an injection-tube connected with the said container, a tub including an annular vessel
